UNITED STATES PATENT OFFICE.

FREDERICK W. CHESSON, OF WATERBURY, CONNECTICUT, ASSIGNOR TO
THE AMERICAN RING COMPANY, OF SAME PLACE.

DESIGN FOR A METAL MOUNT FOR BEDSTEADS.

SPECIFICATION forming part of Design No. 27,478, dated August 3, 1897.

Application filed April 21, 1897. Serial No. 633,192. Term of patent 7 years.

To all whom it may concern:

Be it known that I, FREDERICK W. CHESSON, a citizen of the United States, residing at Waterbury, in the county of New Haven 5 and State of Connecticut, have invented and produced a new and original Design for Metal Mounts for Furniture, &c., (Case 1,) of which the following is a specification, reference being had to the accompanying drawings, in
10 which—

Figure 1 is an elevation, and Fig. 2 a plan, of my design.

The general configuration of the metal mount is round, and the leading features of 15 my design consist in the cylindrical and conical body portion and adjoining coves above and below the same.

The design of the metal mount comprises the cylindrical and conical body portion *a*, the coves *b* *b'* above and below the same, the 20 bead *c*, and bands 2 and 3 above and below said bead, the conical portion *d*, the cove *b*², and bands 4 and 5 above and below said cove, and the acorn 6 at the upper end.

What I claim is—

The design for a metal mount for furniture, &c., as shown and described.

Signed by me this 17th day of April, 1897.

F. W. CHESSON.
